METHOD FOR THE ADMINISTRATION OF MUSCLE RELAXANT DRUGS

Edwin J. de Beer, Tuckahoe, Charles H. Ellis, Scarsdale, and Walter Ide, Eastchester, N.Y., assignors to Burroughs Wellcome & Co. (U.S.A.) Inc., Tuckahoe, N.Y., a corporation of New York

Filed June 18, 1954, Ser. No. 437,631

9 Claims. (Cl. 128—214)

This invention relates to the administration of muscle relaxants for the purpose of producing a state of muscle relaxation during surgical operations.

More particularly the invention is concerned with a device which provides for the automatic release and control of the supply of muscle relaxing agents to a patient as such agents are needed or required to produce a desired degree of muscle relaxation.

In the use of relaxant drugs in anesthesiology, there has been a tendency to overdose due to the use of respiratory arrest as indicating the degree of relaxation. The ordinary methods of administration merely indicate a state of deep relaxation, and do not afford a wide range of safety in a patient with unassisted respiration.

The present invention is based on the fact that a short lasting myoneural blocking agent which is rapidly destroyed in the body and which has no marked cumulative action makes possible a remarkably precise control of the degree of relaxation by regulating the amount of drug administered either by continuous infusion or by intermittent dosage. Basically, the method utilizes a means for administering a relaxant drug in combination with a means for regulating the administration of the drug by using the patient's own muscles to control the dosage rate when subjected to an electrical stimulus. Muscle relaxants as used in surgery, for example, function to paralyze the nerve systems which motivate and control muscle reactions. According to the present invention, the state of relaxation in a patient may be accurately controlled automatically and overdosing prevented through an electrical stimulus which has no substantial effect where an advanced state of paralysis is present. When insufficient relaxant is present in the system to have an effective myoneural blocking action, the electric stimulus applied at a selected motor point according to the present invention will produce a muscular contraction at the point of application which through suitable mechanism applied to a finger or foot of the patient, for example, can be made to release additional relaxant solution as needed to accomplish a uniform state of relaxation.

The invention will be described with respect to succinylcholine chloride commercially sold under the name "Anectine" by the Burroughs Wellcome & Co. (U.S.A.) Inc. It is capable of functioning with any muscle relaxant preparations.

Accordingly, the invention comprises a method and apparatus for administering muscle relaxant drugs which comprises the steps of periodically applying a low amperage electrical stimulus to a muscle motor point of the patient in applying the contractive force of the stimulus when unhindered by a myoneural block to control the admission of additional relaxant into the patient.

In its simplest form, dosage is given intravenously by the customary gravity flow system although other pumping or pressure flow systems could likewise be used.

The drawings illustrate the application of the invention diagrammatically.

In the drawings:

Fig. 1 shows an exemplary apparatus for measurement and supply by motor point stimulation of the index finger and electrical valve control of relaxant supply.

Fig. 2 is a detailed view of a solenoid valve controlling release of relaxant solution through the intravenous supply tube.

Fig. 3 is a kymograph recording showing muscle contraction during the administration of muscle relaxant over a four and one-half hour period.

Referring to Figs. 1 and 2 of the drawings, it will be seen that a suitable device is outlined for carrying out the principles of the invention. It is to be understood that the circuit to the solenoid valve does not close when the patient is paralyzed. When additional relaxant is required, the current to the motor muscle produces a contraction thereby closing the switch to the solenoid valve and releasing additional solution. Preferably, this current is given at 10 second intervals although it will be appreciated that other suitable intervals could likewise be employed.

In the drawings, it will be seen that a container for succinylcholine solution 10 is connected to a needle 11 inserted into the arm of a patient 12 through the medium 25 of a rubber or plastic tubing 13 between the container and the needle. The tube 13 is normally closed by means of a clamp valve 14 at the end of a solenoid 15 normally held in closed position by means of a spring 15a. The functioning of the solenoid 15 is controlled by relay 16 which is connected to a source of electric current at 17 and to a switch diagrammatically shown at 18.

The switch 18 is shown as being adapted to close on flexion of the finger on the hand of the patient 12. Closure of the switch 18 completes a circuit through relay 16.

Connected with the arm of the patient is an electrode 20 having a contact 20a at the muscular motor point and a second indifferent electrode 21 connected with the patient's hand. The two electrodes close a circuit through a motor point stimulator 22 connected to a suitable source of electric power at 23. The motor point stimulator is adapted to deliver a low amperage electrical stimulus to the motor point of the patient's arm. This electrical stimulus is only effective to produce a contraction when the amount of active relaxant drug in the system has become dissipated to an extent at which the desired degree of paralysis is no longer obtained. The contraction of the finger closes the switch 18 which in turn operates the relay 16 energizing solenoid 15 which in turn opens the valve 14, releasing an additional supply of muscle relaxant to flow into the patient.

It will be appreciated that the amount of current flowing from the motor point stimulator electrode 20 and the electrode 21 will depend largely upon the skin resistance of the particular patient. In general, a step-down 55 transformer delivering 25 volts through a 7,000 ohm resistance will deliver a current in the order of one or two milliamperes. This current is adequate to stimulate the nerve centers controlling muscle contraction if the amount of muscle relaxant in the system is not sufficient to block the muscle response.

Referring to Fig. 3, a kymograph recording is shown illustrating the degree of contraction obtained in response to electrical stimulus according to the present invention in an animal over a four hour period. In this case, low 65 amperage stimulus was delivered to a patient at 10 second intervals. In the graph, each up-stroke of the stylus represents the muscle contraction response at a 10 second interval. The extent of the vertical up-stroke is a measure of the force of the muscle contraction obtained at the particular interval. In each instance, the force of this muscle contraction is directly controlled and reduced by the in-

introduction into the patient of muscle relaxant solution through the valve mechanism above described.

It will be observed that during the initial 30 minute period when no relaxant was administered, very strong muscle contraction was obtained in response to each of the applied electrical stimuli. At the end of the 30 minute interval, introduction of muscle relaxant was initiated and it will be observed from that point on to the 270 minute interval that a consistent and sustained degree of muscle relaxation was obtained in the patient. During the period of administration, muscle relaxant solution was only introduced through the patient by operation of the solenoid valve in response to muscle contraction at the high points of the scroll. At least partial paralysis of the patient was achieved during the period when muscle relaxant solution was administered according to the teachings of the present invention. At the end of the 270 minute period, administration was discontinued and the immediately following long strokes of the stylus indicate the recovery period.

The electrical stimulus is preferably applied intermittently at regular intervals to avoid muscle fatigue although under certain conditions, the continuous application of low amperage current during controlled introduction of relaxant may be feasible or even desirable. The electrical means for flow control can be replaced by alternative mechanical or electrical contrivances suitably disposed to control the introduction of muscle relaxant in response to a predetermined muscle contraction and such devices are to be deemed equivalents for purposes of this invention.

What is claimed is:

1. A method for the intravenous administration of muscle relaxant drugs comprising the steps of periodically applying a low amperage electrical stimulus to a muscle motor point controlling a movable body element of the patient and employing the contractive force of the muscle due to the stimulus when unimpaired by myoneural block to control the admission of additional relaxant drug into the patient through movement of said body element.

2. A method for the intravenous administration of muscle relaxant drugs comprising periodically applying a low amperage electrical current to a muscle motor point of the patient to produce a muscle stimulus to a movable body element and administering additional muscle relaxant drug in proportion to the muscle contraction due to said stimulus and movement of the body element.

3. The method set forth in accordance with claim 2 wherein the stimulus is applied to a muscle motor point controlling a finger and the resulting contraction used to open a valve controlling the intravenous administration of the muscle relaxant.

4. The method set forth in accordance with claim 2 wherein the stimulus is applied to a muscle motor point controlling a toe and the resulting contraction used to open a valve controlling the intravenous administration of the muscle relaxant.

5. A method for the parenteral administration of muscle relaxant drugs, which comprises administering a muscle relaxant drug to produce a condition of myoneural block in the subject, applying a low amperage electrical stimulus to the motor point of a muscle controlling an element of the body normally movable by said muscle, and employing the contractive force of the muscle and resulting movement of the body element when unimpaired by myoneural block to control the admission of additional muscle relaxant drug into the patient.

6. A method for the parenteral administration of muscle relaxant drugs set forth in claim 5, wherein the low amperage electrical stimulus is periodically applied to the muscle motor point.

15 7. A method for the parenteral administration of muscle relaxant drugs set forth in claim 5, wherein the movement of the body element is employed to actuate a switch to a relay which is connected with a solenoid valve whereby additional muscle relaxant is admitted to the patient on movement of the body element.

20 8. A method for the parenteral administration of muscle relaxant drugs, which comprises administering a muscle relaxant drug to produce a condition of myoneural block in the subject, applying a low amperage electrical

25 stimulus to the motor point of a muscle controlling a finger normally movable by said muscle, and employing the contractive force of the muscle and resulting movement of the finger when unimpaired by myoneural block to control the admission of additional muscle relaxant drug into the patient.

30 9. A method for the parenteral administration of muscle relaxant drugs, which comprises administering a muscle relaxant drug to produce a condition of myoneural block in the subject, applying a low amperage electrical

35 stimulus to the motor point of a muscle controlling a toe normally movable by said muscle, and employing the contractive force of the muscle and resulting movement of the toe when unimpaired by myoneural block to control the admission of additional muscle relaxant drug into the patient.
